12 Claims

ABSTRACT OF THE DISCLOSURE

Pile hammer leads are adjusted side-to-side to full batter angles of inclination, being pivoted to a carriage which rides over a short straight beam pivoted in line with the bottom brace of the rig and which is extensible from this pivotal mounting to reach the leads out to the desired angles of inclination and retractable to reduce the sidewise projection, for operation in a restricted area.

The general objects of this invention have been to provide practical and effective equipment for operating a pile hammer in areas limited in operating space, such as, for instance, would prevent the use of conventional pile driving equipment having the long curved "moonbeam" form of batter adjustment.

Other desirable objects attained by the invention and the novel features of construction, combination and arrangement of parts embodying the invention are set forth and will appear in the course of the following specification.

The drawings accompanying and forming part of the specification are illustrative of a preferred embodiment of the invention, but as will appear, the structure may be modified and changed as regards the present illustration; all within the true intent and scope of the invention as hereinafter described and claimed.

FIG. 1 is a front elevation of one of the new universal batter adjustments with broken lines indicating reverse sidewise adjustment of the batter angle.

FIG. 2 is a side view of the machine.

FIG. 3 is an enlarged broken sectional view on substantially the plane of line 3—3 of FIG. 2.

FIG. 4 is a broken plan view on substantially the plane of line 4—4 of FIG. 2.

FIG. 5 is a perspective view of the carriage to which the lower end of the lead is pivoted.

FIG. 6 is a perspective view of the head which carries 50 the beam for the carriage.

FIG. 7 is a broken sectional view across the beam showing the pivoted supporting head at one side and the carriage for the leads at the opposite side.

FIG. 8 is a sectional detail of the stop pin for locking 55 the beam in different adjusted positions in the supporting head.

FIG. 2 shows a lead 10 for a pile hammer, pivoted at the top at 11 on the point of a beam 12 for fore and aft batter under control of the bottom brace 13, which may be of the powered type shown in Patent No. 3,344,-867 of Oct. 3, 1967.

FIG. 1 shows the lead pivoted at 14 in a fore and aft direction for side batter.

The lower end of the lead is pivoted at 15 to a carriage 16 which rides over a short straight beam 17, which is longitudinally shiftable in a head 18, rotatably mounted on an axis 19 in line with the bottom brace.

The beam 17 is shown as an H beam, disposed with the web 20 of the same horizontal, thus to locate the inner pair of flanges 21 between upper and lower rollers 22, 23 and front and back rollers 24, 25, on the rotatable sup-

2

porting head 18 and flanges 26 at the front engaged by top and bottom rollers 27, 28 and back rollers 29 on the travelling carriage 16.

FIGS. 6 and 7 show the rotatable supporting head 18 as carried by a spindle 19, mounted to turn on the end 5 of the bottom brace 13.

A bridle 30 for supporting and steadyng the ends of the beam is shown in FIG. 1 as run up over a guide sheave 31 on the center 14 on the point of the beam.

To "spot" the beam in centered position on its angularly adjustable support and in definite extended and retracted positions, lock pins 32, FIGS. 3, 4 and 8, are provided which can be inserted into openings 33 in the beam, at opposite sides of the supporting head 18.

The beam may be shifted manually or by power and may be locked in the centered or off-center positions by the locking pin or pins 32 described.

The side batter adjustment of the leads is effected in the illustration by drag lines 35, 36, FIGS. 3 and 4, 20 adjustably connected at 37, 38, with opposite sides of the travelling carriage and run over sheaves 39, 40 on opposite ends of the beam and over lower and upper guide pulleys 41, 42, 43 and 44, down to a reversible motor driven drum 45, FIG. 2 in the cab of the crane.

With the stop pins in place at opposite sides of the supporting head, the beam will be held against longitudinal movement in the head and the pull on the lines 35, 36 will have the effect of shifting the lead positioning carriage along the anchored beam.

On removal of the lock pins, the beam will be freed for longitudinal adjustment in the head and the powered shifting lines 35, 36 may then be used to shift the beam outward and inward in respect to the supporting head.

The cables may thus be used for the double purpose of longitudinally adjusting the beam to any desired extent or shifting the batter setting carriage on the beam.

The beam may be relatively short as compared to the ordinary "moonbeam," but may for instance be full 20 feet so as to reach, when extended, as far or further than a "moonbeam."

This 20 foot beam may be retracted to or past the center of support to fully avoid interfering structure that would prevent operation of a moonbeam in such a location.

In operating the system, the support head is left free to turn on its axis so that with pull on line 35 or 36 the carriage will apply pressure to rock the beam one way or the other as necessary to keep the beam lined up for straight travel of the carriage along the beam.

What is claimed is:

1. Pile hammer batter adjustment means comprising the combination with a crane having a boom and a pile hammer lead pivotally suspended from the point of the boom for fore and aft and side batter, of a pivotally mounted angularly adjustable supporting head, beneath the lead, a beam longitudinally adjustable on said supporting head transversely of the axis of said angular adjustment of the supporting head, a side batter adjusting carriage longitudinally shiftable on said beam and pivotally connected with the lower end of said lead on an axis parallel with the fore and aft pivotal axis of the lead, and means for effecting shifting of the carriage on the beam to different angles of side batter or centering of the lead to vertical drive position.

2. The invention according to claim 1 in which said beam is a length of H beam having flanges at opposite sides connected by a web and in which said beam is disposed with said web in horizontal position and the flanges vertical, with the flanges at one side engaged in said sup-

porting head and the flanges at the opposite side engaged by said carriage.

3. The invention according to claim 1 with readily releasable means for locating and holding said beam in different adjusted positions on said supporting head.

4. The invention according to claim 3 in which said means includes stop pins at opposite sides of the supporting head engageable in selected openings in the beam.

5. The invention according to claim 1 with said means including cable connections with said carriage and extending over pulleys on the ends of the beam to means for motivating said cables.

6. The invention according to claim 1 with said means including connections for effecting shifting of the beam in said supporting head.

7. The invention according to claim 1 with means for supporting and stiffening the ends of the beam and flexible to shifting adjustments of the beam on the supporting head.

8. The invention according to claim 7 with said supporting and stiffening means including cable connections extending from the ends of the beam up to the point of the boom.

9. The invention according to claim 1 with rollers on said head in guiding and supporting engagement with said beam and rollers on said carriage in supported engagement with the beam.

10. The invention according to claim 1 in which said beam is a short straight length of H beam.

11. The invention according to claim 1 in which said supporting head is free to turn on its pivotal axis and

10

15

30

51-711

said means for effecting shifting of the carriage includes means for turning the head to keep the beam lined up for travel of the carriage along the same.

12. Pile hammer batter adjustment means comprising the combination with a crane having a boom and a pile hammer lead pivotally suspended from the point of the boom for fore and aft and side batter, of a pivotally mounted angularly adjustable supporting head, beneath the lead, a beam longitudinally adjustable on said supporting head transversely of the axis of said angular adjustment of the supporting head, a side batter adjusting carriage longitudinally shiftable on said beam and pivotally connected with the lower end of said lead on an axis parallel with the fore and aft pivotal axis of the lead, and controllable means for effecting shifting of said beam in said supporting head, movement of said carriage along the beam and rotary adjustment of said supporting head, in accordance with direction and extent of travel of the carriage along the beam.
